2 SHEETS-SHEET 2.

UNITED STATES PATENT OFFICE.

HENRY HENNIG, OF PATERSON, NEW JERSEY.

DYEING OR WASHING MACHINE.

1,115,072.

Specification of Letters Patent. Patented Oct. 27, 1914.

Application filed August 10, 1911. Serial No. 643,306.

To all whom it may concern:

Be it known that I, HENRY HENNIG, a citizen of the United States, and resident of Paterson, in the county of Passaic and State 5 of New Jersey, have invented a new and useful Improvement in Dyeing or Washing Machines, of which the following is a specification.

The object of this invention is to provide 10 certain improvements in the construction, form and arrangement of the several parts of a dyeing or washing machine whereby the liquid within the tank may be thoroughly agitated by the introduction of jets of air, 15 in which the yarn sticks are readily removable and in which the upper and lower rows of yarn sticks are located at a lesser distance from each other than the lengths of the skeins so as to permit a thorough treatment 20 of the yarn without permitting it to become tangled.

In the accompanying drawings, Figure 1 represents the machine in top plan, a portion 25 of one of the deflecting plates at the top of one of the side flues being broken away to show the parts beneath the same, Fig. 2 is an end view of the machine, Fig. 3 is a vertical longitudinal section through the machine, a portion of one of the vertical 30 side partitions being broken away to show the parts beyond the same, Fig. 4 is a transverse vertical section through the machine, Fig. 5 is a detail end view of the yarn frame showing the means for releasing the yarn 35 sticks, and Fig. 6 is a detail cross section in the plane of the line A—A of Fig. 5.

The side walls of the tank are denoted by 1, 2, its end walls by 3, 4, and its bottom by 5. This tank may be reinforced at different 40 points by encircling bands 6 and vertical bars 7 suitably secured together. Vertical flues 8, 9, are formed along the sides of the tank by providing vertical partitions 10, 11. Deflecting plates 12, 13, are located at the 45 tops of the side flues 8, 9, for directing the up-flowing liquid and air laterally and downwardly into the main portion of the tank.

The means for agitating the liquid within 50 the tank by means of jets of air may be constructed and arranged as follows:—A main air inlet 14 is connected by a four-way coupling 15 directly to a vertical pipe 16 and to two vertical pipes 17, 18, through 55 horizontal branches 19, 20. These three vertical pipes 16, 17, 18, are provided with

manually controlled valves 21, 22, 23, for regulating the supply of air through said pipes. The pipe 16 is connected to two horizontally arranged pipes 24, 25, extending 60 along the interior of the tank near its bottom at points a considerable distance from the side walls of the tank. The pipes 17 and 18 communicate with two horizontally arranged pipes 26, 27, extending along within 65 the vertical flues 8 and 9 near the bottoms of said flues. These pipes 24, 25, 26, 27, are all provided with nozzles for directing jets of air upwardly. The jets of air issuing from the nozzles of the pipes 26, 27, serve 70 to cause the liquid to flow upwardly with the air through the flues 8 and 9 until they come in contact with the deflecting plates 12, 13, where they are directed laterally and downwardly into the body portion of the 75 tank. The jets of air issuing from the pipes 24, 25, cause an upward circulation of the liquid intermediate the flues and the two opposing currents meet in the interior of the tank thus causing a complete agitation 80 of the liquid.

The yarn frame comprises upper and lower horizontally arranged rows of yarn sticks 28, 29, supporting cross bars 30, 31, and upper and lower pairs of cross plates 85 32, 33, secured to depending pairs of side bars 34, 35. The pairs of side bars 34, 35, are connected by side extensions 36, 37, of the upper pair of cross plates 32. These side extensions 36, 37, together with the 90 cross plates 32, form a loop which gives rigidity to the yarn frame. The upper cross plates 32 are provided with horizontal series of holes 38 for receiving the opposite ends of the yarn sticks 28 and the lower 95 cross plates 33 are provided with horizontal series of holes 39 for receiving the ends of the yarn sticks 29. These yarn sticks are held against removal by keepers. In the present instance, the keepers 40 at one 100 end of the yarn sticks 28 and 41 at the corresponding ends of the yarn sticks 29 are inimovable while the keeper 42 for the other ends of the yarn sticks 28 and the keeper 43 for the corresponding ends of the yarn 105 sticks 29 are movable. One way of moving the keeper 42 out of its yarn stick retaining position is shown herein in which the keeper is hinged at 44 at one end and engages a notched lug 45 at its other end. 110 The upper and lower series of yarn sticks are arranged at a lesser distance from each

- other than the length of the yarn skeins so that a thorough treatment of the yarn by the liquid is insured without liability of causing the yarn to be entangled.
- 5 The means which I have shown herein for raising and lowering the frame comprises a longitudinally arranged bar 46 attached to any suitable lifting mechanism, not shown, the ends of which bar are engaged with eyes 47, 48, secured to the supporting cross bars 30, 31. To further strengthen the yarn frame an encircling band 49 may be provided for the upper pair of cross plates 32 and their extensions 36, 37.
- 10 15 From the above description it will be seen that means are provided for securing a thorough agitation of the liquid in the tank by jets of air. It will also be seen that a yarn frame is provided which is of such an open construction as to permit a free and unimpeded circulation of the liquid through the yarn. It will also be seen that a means is provided for rapidly inserting and removing the yarn sticks.
- 20 25 It is evident that various changes might be resorted to in the construction, form and arrangement of the several parts without departing from the spirit and scope of my invention; hence I do not wish to limit myself strictly to the structure herein set forth, but

What I claim is:—

1. In a machine for washing and dyeing, a tank for the liquid, two oppositely arranged vertical flues spaced from the top and bottom and secured to said tank along its side walls, an independent air pipe lo-

cated near the bottom of each flue to direct jets of air upwardly through the liquid in the flues, and inclined deflecting plates secured to the side walls above the tops of the flues for directing the liquid and air laterally and downwardly into the center of the tank.

2. In a machine for washing and dyeing, 45 a tank for the liquid, two oppositely arranged vertical flues spaced from the top and bottom and secured to said tank along its side walls, independent air pipes located near the bottom of each flue and in the 50 body of the tank for directing independent jets of air through the liquid in the flues and through the liquid in the body portion of the tank, and inclined deflecting plates secured to the side walls above the tops of 55 the flues for directing the air and liquid laterally and downwardly into the center of the tank.

3. In a machine for washing and dyeing, 60 a tank for the liquid and a yarn frame comprising yarn sticks, a pair of cross plates having holes for receiving the ends of the sticks and keepers carried by the cross plates for preventing unintentional removal of the sticks, one of said keepers being movable to release the sticks.

In testimony, that I claim the foregoing as my invention, I have signed my name in presence of two witnesses, this 7th day of August 1911.

HENRY HENNIG.
